UNITED STATES PATENT OFFICE.

GROVER CLEVELAND LOENING, OF NEW YORK, N. Y.

LANDING-GEAR FOR AEROPLANES.

1,162,177.

Specification of Letters Patent. Patented Nov. 30, 1915.

Application filed June 30, 1915. Serial No. 37,151.

To all whom it may concern:

Be it known that I, GROVER CLEVELAND LOENING, a citizen of the United States, and a resident of the city, county, and State of New York, have invented certain new and useful Improvements in Landing-Gears for Aeroplanes, of which the following is a specification.

The object of the invention is to improve the landing gears of aeroplanes, and more particularly to secure an especially simple and light, yet strong, construction and to provide for advantageous application and distribution of the landing stresses. These ends are attained by certain novel features of construction and relationship and combinations of parts, which will now be briefly explained by reference to a preferred embodiment, and hereinafter more particularly pointed out in the claims.

In the drawings illustrating the said preferred embodiment and forming a part hereof: Figure 1 is a side elevation of an aeroplane provided with my landing gear, the latter being in vertical longitudinal section, the plane of the section intersecting the axle intermediate the strut frames; Fig. 2 is a front elevation of Fig. 1 with portions of the wings broken away; Fig. 3 is an enlarged vertical longitudinal section taken in the plane of the bridge and anchorage of Fig. 4, the clip and elastics being shown in elevation; Fig. 4 is a front elevation of the parts shown in Fig. 3, the adjacent wheel and protecting washer being in section; and Fig. 5 is a fragmentary perspective view looking at the outer side of the lower portion of the strut frame shown in Figs. 3 and 4, showing the slotted plates and anchorage.

In these views *a* represents the body, of suitable construction, and *b* the planes.

The embodiment of my landing gear herein illustrated comprises two approximately V-shape strut frames 2, which project downward from opposite sides of the body, and which may be inclined outward as shown in order to secure a comparatively wide wheel base. Each strut frame comprises two converging struts 3 and 4, preferably of wood and of stream-line cross-section, the upper ends of the struts being rigidly secured to the body, and the proximate, lower ends of each pair being in abutting relation, as indicated in Fig. 3. The lower end of the V frames are preferably cut off on a straight line for the reception of the anchorages pres-

ently to be described. The members of the frames thus formed are united by slotted plates 5, disposed in pairs at opposite sides of the lower ends of each pair of struts, to 60 which they are affixed by bolts passing through the plates and struts, certain of the bolts being designated 6. Portions of these plates overlap the spaces between the struts of the frames, and in these portions are 65 elongated slots 7 ranging upward and preferably somewhat rearward, to receive and guide the axle 8 of wheels 9. The relative upward movement thus permitted to the axle upon alighting is yieldingly opposed by 70 resilient shock-absorbing means, composed preferably of a number of separate elastics 10, known in the art. The said elastics are connected at their upper ends to bridges 11, resting on the portions of the axle which 75 project beyond the strut frames, and at their lower ends to anchorages 12 fixed to the outer sides of said frames at their lower ends beneath the said axle portions. The said bridges, which, broadly, are not new in 80 themselves, may consist each of spaced, centrally notched plates 13 disposed in vertical planes transversely of the axle and connected by a half tubular bearing 14 and spanned by a row of transverse pins 15 for the reception 85 of the elastics. A bridge of this form merely rests on its support and can therefore be readily taken off and replaced, but I find that it is inclined to chatter; and to overcome this drawback I have provided a split collar 90 or clip 28, which encircles the bearing 14 and the axle and thus holds the bridge reliably without sacrificing the advantage of ready removability.

Each of the anchorages 12 is shown as 95 constituted by two bent plates 16 and 17, this construction being of especial advantage for its ease of production and repair, and being specifically claimed hereinafter, though an integral formation is not necessarily excluded. The inner of these plates 16 is applied against the outer face of the corresponding strut frame, that is to say, against the outer slotted plate 5, while the other anchorage plate 17 is carried outward from the said plate 16, so that a channel portion is formed, the sides of which support a row of pins 18 for the elastics. The plate 17 of each anchorage is also extended inward (at 19) as a bearing beneath the lower end of 100 the frame, and thence upward (at 20) at the inner side of the frame, against the inner

of the slotted plates 5. The plate 16 and the portion 20 of the inward extension of the plate 17 are thus disposed at opposite sides of the strut frame, enabling both plates to be secured to the frame and united to each other by a set of bolts 24, which also pass through the slotted plates 5 and serve in part to unite the latter to the struts and to hold the struts together, thus economizing parts and saving weight.

The inner portions 20 of the anchorages preferably terminate in projecting flanges or lugs 22. These serve for the reception of the lower ends of tension wires 23, which extend diagonally and laterally upward, in crossing relation, inwardly of the strut frames, to the body α , to which their upper ends are secured at points laterally remote from the corresponding anchorages. In this way a portion of the landing stresses transmitted through the elastics 10 to the anchorages is in turn directly transmitted to the tension wires and by them distributed over the body or frame of the machine. Any tendency to lateral bending or tilting of the strut frames is thus overcome, the portion of the stresses which is not taken up as a tension in the wires acting as a thrust in the plane of each frame. Moreover, owing to the direct connection of the diagonal tension wires to the anchorages, the stresses acting upon these parts are equalized at opposite sides of the strut frames, and consequently the tendency of the elastics to displace or distort the anchorages is overcome. It will be observed, also, that the bearing portions 19 beneath the frames relieve the bolts 24 of shearing stresses. Furthermore the anchorages, because of their angular or flanged formation supply lateral beam strength to the lower ends of the strut frames, strengthening the latter against stresses which might tend to displace the struts in relation to each other. To complete the bracing of the structure, the strut frames are preferably connected by the transverse thrust and tension members comprising a bar 25 and a wire 26.

Where the axle is solid or bodily movable as illustrated, there is an opportunity for side-play, which is desirable, and in order to protect the wheels from contact with the anchorages I mount on the axle at the inner sides of the wheels large washers 27. It is to be understood, however, that I do not limit myself to bodily movable axles, as divided axles hinged in the middle are well known in the art and could obviously be used in my landing gear if desired. The said washers are preferably of dished formation, their concave sides being next the wheels, and as shown may be confined at their central apertures between collars 29 on the axle and the inner ends of the hubs 30 of the wheels. In this way the washers

are themselves held out of contact with the spokes 31 in addition to preventing the latter from touching the anchorages.

In general, the invention is not necessarily confined to the precise forms of construction shown, since various modifications and substitutions within the spirit of the invention will suggest themselves to those skilled in the art.

What I claim as new is:

1. In a landing gear for flying machines, laterally spaced downward projecting V strut frames, each comprising a pair of downward converging struts and a pair of slotted plates disposed at opposite sides of the proximate ends of said struts and bolted through and uniting the same, and a wheel axle guided in said slotted plates, in combination with anchorages united with said slotted plates and held in place by the same bolts, bridges supported on the axle, and elastic bands connecting said anchorages and bridges.

2. In a landing gear for flying machines, the combination of laterally spaced downward projecting V strut frames having slotted plates secured to the sides thereof at the bottom, a wheel axle guided in said plates, anchorages united with said slotted plates at the outer sides of the strut frames, bridges supported on the portions of the axles extending outwardly from the strut frames, and elastics connecting said anchorages and bridges.

3. In an aeroplane, the combination with a body, of laterally spaced V strut frames comprising downwardly convergent struts and slotted plates united therewith at their proximate lower ends, a wheel axle guided in said plates, anchorages bolted to the outer sides of the strut frames at their lower ends, said anchorages having inward extensions, resilient means connected to said anchorages for opposing relative upward movement of the axle, and tension wires secured to the said inward extensions of the anchorages and extending therefrom diagonally and laterally upward and secured to the body.

4. In a flying machine, the combination of laterally spaced downward projecting strut frames, a wheel axle guided for relative upward movement in the lower portions of said strut frames, anchorages secured to the lower ends of said frames at the outer sides thereof, bridges on the portions of the axle projecting outward from the strut frames, elastics connecting said anchorages and bridges, wire attachments disposed inwardly of the strut frames and united with said anchorages, and tension wires secured to said wire attachments and extending diagonally and transversely upward therefrom, inward of the strut frames, to suitable points of attachment on the machine above and laterally remote from their respective anchorages.

5. In an aeroplane, a landing gear comprising laterally spaced downward projecting strut frames, a wheel axle guided for upward movement in the lower portions of said frames, anchorages secured to the lower ends of said frames, each of said anchorages comprising a channel portion containing a row of transverse pins for the reception of elastics to oppose relative upward movement 10 of the axle, said channel portion being disposed at the outer side of the corresponding frame, the anchorage comprising also portions extended inward beneath the lower end of the frame and upward at the inner side 15 thereof, and bolts passing through the lower ends of each strut frame and the portions of the corresponding anchorage at opposite sides thereof to unite the anchorage to the frame.
- 20 6. In a flying machine, the combination of laterally spaced downward projecting strut frames, a wheel axle guided for upward movement in the lower portions of said frames, anchorages secured to the lower ends 25 of said frames beneath the axle, each of said anchorages comprising a channel portion containing a row of transverse pins for the reception of elastics to oppose relative upward movement of the axle, said channel 30 portion being disposed at the outer side of the corresponding frame, the anchorages also comprising portions disposed beneath the lower end of the frame and at the inner sides thereof, and tension wires secured to 35 the portions of said anchorages inward of the frames and extending diagonally and laterally upward to suitable points of attachment on the machine.
7. A landing gear for flying machines, 40 comprising the combination of laterally spaced downward projecting V strut frames, each comprising a pair of converging struts and slotted plates bolted to the sides of the proximate lower portions thereof, an axle 45 guided for relative upward movement in said slotted plates, resilient means for yieldingly resisting such movement, anchorages for said resilient means disposed at the sides of the strut frames below the axle, and bolts 50 passing transversely through the anchorages and through the slotted plates and struts and serving for the uniting of the struts and the securing of the anchorages and plates.
- 55 8. A landing gear for flying machines, comprising the combination of laterally spaced downward projecting V strut frames, each comprising a pair of converging struts and slotted plates at the sides of the proximate lower portions thereof, an axle guided 60 for relative upward movement in said slotted plates, resilient means for yieldingly resisting such movement, anchorages for said resilient means at the outer sides of the strut 65 frames below the axle, tension wire-attach-
- ing means at the inner sides of the lower portions of the strut frames, transverse bolts passing through the lower portions of the struts and the slotted plates and also securing the anchorages and wire attachments, 70 and tension wires secured to said attachments and extending diagonally and laterally upward to suitable points of attachment on the machine.
9. A landing gear for aeroplanes comprising the combination of laterally spaced downward projecting V strut frames, each comprising a pair of converging struts, an axle guided for relative upward movement in the lower portions of said frames, resilient 75 means for yieldingly resisting such movement, and anchorages for said resilient means comprising members of angular cross-section bolted across the sides of the meeting ends of said struts with portions 80 disposed beneath the same and affording lateral beam strength to the frames.
10. A landing gear for flying machines, comprising the combination of laterally spaced downward projecting strut frames, 85 an axle guided for relative upward movement in the lower portions of said frames, elastics acting to hold the axle down, anchorages for said elastics secured to the outer sides of the lower ends of the strut frames 90 and having bearing portions extended inward beneath the same, and tension wires secured to the inner portions of said anchorages and extending diagonally and laterally 95 upward to suitable points of attachment on the machine.
11. In an aeroplane, a landing gear comprising the combination of laterally spaced downward projecting strut frames, a wheel axle guided for upward movement in the lower portions of said frames, anchorages secured to the lower ends of said frames beneath the axle, each of said anchorages comprising two plates supporting between them 105 a row of pins for the reception of elastics to oppose relative upward movement of the axle, the inner plate of each anchorage being applied against the outer side of the corresponding frame and the outer plate being carried outward away from the inner plate 110 and being extended inward beneath the lower end of the frame and upward at the inner side thereof, and bolts passing through the lower ends of the frames and the portions of the anchorage plates at opposite 115 sides thereof.
12. In a flying machine, a landing gear comprising the combination of laterally spaced downward projecting strut frames, a wheel axle guided for upward movement 120 in the lower portions of said frames, anchorages secured to the lower ends of said frames beneath the axle, each of said anchorages comprising two plates supporting between them a row of pins for the reception 125

of elastics to oppose relative upward movement of the axle, the inner plate of each anchorage being applied against the outer side of the corresponding frame and the outer plate being carried outward away from the inner plate and being extended inward beneath the lower end of the frame and upward at the inner side thereof and terminating in a projecting flange, bolts passing through the lower ends of the frames and the portions of the anchorage plates at opposite sides thereof, and tension wires secured to said flanges and extending diagonally and laterally upward to suitable points of attachment on the machine.

13. In an aeroplane, a landing gear comprising, in combination, laterally spaced downward projecting V strut frames, each comprising a pair of converging struts, slotted plates at the sides of the meeting ends of said struts, an axle guided for relative upward movement in said slotted plates, resilient means for yieldingly resisting such movement, anchorages for said resilient means secured to the frames below the axle,

each of said anchorages comprising two plates, one of which is applied against one side of the frame and the other plate having a portion spaced from the first and cooperating therewith to support a row of 30 anchorage pins, and being further provided with a portion disposed beneath the lower ends of the struts and extended upward at the opposite side thereof, and bolts passing transversely through the portions of said 35 anchorage plates at opposite sides of the frames, through the struts, and also through the slotted plates lying therebetween.

14. In an aeroplane landing gear, the combination with laterally spaced frames, a 40 wheel axle guided for relative upward movement therein, elastics for yieldingly resisting such movement, and bridges for receiving the upper ends of said elastics, said bridges resting on the axle so as to be removable therefrom without removing the wheels, of clips encircling the axle and removably securing the bridges thereto.

GROVER CLEVELAND LOENING.
